UNITED STATES PATENT OFFICE.

EDMUND A. HEY, OF LA GRANGE, AND JOHN G. LE PERE AND LYLE K. WEBBER, OF DECATUR, ILLINOIS, ASSIGNEES TO THE WILLIAMS SEALING CORPORATION, OF DECATUR, ILLINOIS, A CORPORATION OF CONNECTICUT.

SEMAUTOMATIC BOTTLE-CAPPING MACHINE.

Application filed May 3, 1919. Serial No. 294,572.

To all whom it may concern:

Be it known that we, EDMUND A. HEY, of La Grange, in the county of Cook and State of Illinois, JOHN G. LE PERE, of Decatur, in the county of Macon and State of Illinois, both citizens of the United States, and LYLE K. WEBBER, of Decatur, in the county of Macon and State of Illinois, a subject of the King of Great Britain, have 10 invented certain new and useful Improvements in Semiautomatic Bottle-Capping Machines, of which the following is a specification.

This invention relates generally to bottle 15 capping machines and more particularly to a semi-automatic capping machine; that is, one in which a bottle is placed in the machine by hand and likewise the bottle cap, the bottle being moved into engagement with 20 the cap and the cap locked thereon by a treadle operated mechanism.

The invention relates also to a machine adapted to operate upon a cap having a movable locking lever.

25 One object of the present invention is to provide a machine embodying these characteristic features, which will be simple and efficient in operation and at the same time durable and inexpensive.

30 Another object of the invention is to provide a machine of this sort which will accommodate various sizes of bottles and also various sizes of caps, within certain limits.

Another and very important object of 35 this invention is to regulate the movement of the bottle in bringing the same into engagement with the cap, so as to avoid undue pressure, and breakage which might result therefrom; and a still further object is to 40 provide for maintaining the bottle in a fixed position while the lever turning mechanism is operative, said lever turning mechanism being independent to a certain extent of the bottle moving means.

45 Another object of the invention is to provide a machine of this kind in which the lever turning mechanism can be operated by hand if so desired.

With these various objects in view, the 50 invention consists in the novel features of construction of the various parts, and in the manner of combining or arranging the same; all of which will be fully described

hereinafter and set forth in the appended claims.

In the drawings forming a part of this specification, Fig. 1 is a side elevation of a bottle capping machine constructed in accordance with this invention; Fig. 2 is a front elevation of the same; Fig. 3 is a detail sectional view partly in elevation; Fig. 4 a sectional plan view on the line 4-4 of Fig. 3; Fig. 5 is a horizontal sectional view on the line 5-5 of Fig. 3; Fig. 6 is a front view of a chuck; Fig. 7 is a side view of the same; Fig. 8 is a sectional plan view on the line 8-8 of Fig. 6; Fig. 9 is a detail view of lever turning finger; Fig. 10 is a detail view of bottom plate of chuck with gripping fingers detached; and Fig. 11 is a detail view of cam and lever for raising bottle support.

In constructing a machine in accordance with the present invention we provide an upright frame A having a flat base A' of suitable dimensions and which is preferably bolted or spiked to the floor in order to maintain the machine rigid. The frame which is in the nature of a standard is provided with a horizontal projection A² 75 through which the table adjusting means work, and the frame is also constructed with projections A³ and A⁴ in which the chuck and plunger shaft work.

A table B, upon which the bottle to be 85 capped, is placed, is carried at the upper end of a screw C and at its inner end the table B is cut out as shown at B' to straddle the front side of the upright frame, thus utilizing said frame as a guide during the vertical movements of the table. The upper face of the table is preferably covered by a pad of rubber or other suitable material 90 in order to guard against breakage of the bottle.

A bottle gauge D is fastened to the upper 95 face of the table, said gauge being preferably angular in shape, as shown, and its size and shape will be governed by the size and shape of the bottle which is to be 100 capped, but for all ordinary structures of bottles we have found that the angular form of gauge is best adapted for the purpose, and this type of gauge is, of course, made in various sizes to accommodate different sizes of bottles. The gauge D is 105

provided with rearwardly extending arms D' slotted at D² and through which the fastening bolts are adapted to pass. This gauge will be so positioned upon the table 5 with reference to the operative parts of the machine that the bottle when contacting with the gauge will be centered in direct vertical alignment with the chuck so that the bottle cap carried by said chuck will be 10 centrally placed upon the mouth of the bottle.

The screw C, which carries the table at its upper end, is threaded through the table 15 lifting sleeve or nut E, flanged at its lower end as shown at E', for engagement with the lifting lever F; and to the upper end of this sleeve E is secured a hand wheel G by means of which the sleeve can be turned to raise or lower the screw for the purpose 20 of adjusting the table to the proper operative level according to the height of the bottle to which the cap is to be applied, and this hand wheel G is preferably connected to the upper ends of the screw by means of 25 radial set screws working in radial bores produced in the hand wheel, the ends of the screws seating in tapered sockets produced in the sleeve to receive them. This hand wheel also limits the downward movement 30 of the sleeve in the projection A².

A lock nut H is arranged upon the screw and is adapted to be turned down firmly upon the hand wheel after the table has been adjusted to its proper height.

The table is lifted by means of a lever F which is pivoted within the lower portion 40 of the upright supporting frame upon a horizontal shaft F', this lever being centrally arranged as shown and bifurcated at its forward or outer end F² in order to straddle the screw C and engage the flanged end E' of the table lifting sleeve E.

The rear or inner end of this lever F is 45 also bifurcated as shown at F³ to receive a roller F⁴ which contacts with the periphery of a cam I. The lever F is an elbow lever as shown and it is obvious that when the cam I operates upon the inner end of the lever to depress the same the outer end of 50 the lever will be raised carrying with it the sleeve, screw and table.

The cam I is substantially circular in 55 shape for the greater portion of its circumference but at the point I' there is a flat face extending from a point on the circumference inwardly and there is also a flat face I² which meets the flat face I', this flat face I² being inclined to the radius about 45°. The roller upon the end of the lever normally 60 rests against the inclined face I² of the cam and consequently during the initial movement of the cam in the direction indicated, the lever will be rocked so as to elevate the table a definite extent, and then, 65 during the remaining movement of the cam

the table will be held stationary at the limit of its upward movement.

The cam I is mounted upon a horizontal shaft K passing through the lower portion 70 of the supporting frame and projecting laterally some distance at each side of said supporting frame. The cam however is rigidly connected to the shaft within the cored portion of the supporting frame and is centrally arranged so as to operate upon the 75 inner or rear end of the lifting lever.

Upon the outer ends of the shaft K are mounted the foot treads L, the upper ends 80 of said treads being rigidly connected to the ends of the shaft and these treads are then curved rearwardly and downwardly as shown at L' terminating in a horizontal foot receiving portion L² and in operation these treads are pushed backwardly by the backward and downward push of the operator, 85 turning the cam in the direction indicated causing the lever to be rocked and the table elevated the proper amount to bring the bottle into operative relation with the cap receiving chuck, and by the proper adjustment of the table, the amount of movement imparted by the cam will be sufficient to give the bottle all the vertical movement it requires.

The caps to be applied to the bottles are 90 made of sheet metal in accordance with U. S. Patent No. 1,108,959, granted September 1, 1914, and have a depending slotted skirt surrounded by a ring attached thereto, said 95 ring carrying a lever which is operated to contract the ring and secure the cap upon the mouth of the bottle, and caps of this character are thrown into the hopper M from which they emerge upon a delivery incline M' and from which they are picked, 100 one at a time, by the operator and inserted into the cap receiving chuck N.

This chuck comprises a horizontal plate N' which is secured to the underside of a pressure block O, and this plate N' is formed 105 with a curved depending guide N² into which the cap is guided and against which it is held by means of the spring gripping fingers N³, pivoted at N⁴, and actuated at 110 their rear or inner ends by means of a coil spring N⁵ which is located in a horizontal bore produced in the rear end of the plate N'. The gripping fingers N³ are positioned 115 upon laterally projecting lugs N⁶ carried by the plate N and are held against displacement by pins N⁷. The forward or outer ends of the gripping fingers are peculiarly curved as shown at N⁸ in order to grip the cap which is placed therebetween, the forward 120 ends of these gripping fingers converging slightly towards each other as shown, and as the cap is inserted along the bottom of the plate N' and carried toward the depending guiding flange N², the forward ends of 125 the gripping fingers will be forced apart 130

sufficiently to permit the introduction of the cap and will automatically close again to prevent its dislocation, and when the cap has been inserted between the gripping fingers, and forced back into engagement with the depending guide and flange N^2 , it will be held properly centered, so that, as the bottle is moved upwardly by the table the mouth of the bottle will properly enter the cap which is to be secured thereon.

As previously stated the bottle is positioned by means of a gauge D and the cap is positioned by means of the guiding or gauge flange N^2 , and these two parts are so arranged with reference to each other and their size and shape governed by the size of the cap to be applied, that the bottle held against the gauge will correctly enter the cap correctly placed in its guide or gauge.

It will of course be understood that the chuck comprising the plate, guide and gripping fingers will be made in varying sizes to accommodate caps of different sizes.

The pressure block O will be the same for all sizes and this block is formed at its lower forward end with a forwardly projecting lip O' against which the lever of the cap is adapted to rest when said cap has been properly inserted in the chuck. The pressure block is preferably square in cross section and works in the correspondingly shaped groove A^5 cut in the forward face of the projection A^2 . A bearing plate O^2 is bolted to the end of the projection to hold the square portion of the pressure block in the groove during its movement up and down. The lower portion of the pressure block is somewhat larger than the upper portion, there being an intervening shoulder O^3 which will serve to limit the upward movement of said block.

A plunger shaft P is rigidly fastened in the upper end of the pressure block and extends upwardly through a bushing Q screwed into the end of the projection A^4 and between the bushing Q and the end of the pressure block, and surrounding the plunger rod, is a pressure spring R , said spring bearing directly upon the upper end of the pressure block and exerting a downward pressure thereon, this spring however yielding upwardly as the bottle is moved up into the cap and the tension of this spring can be gauged by adjusting of the bushing, and in this manner, the proper degree of tension to affix the cap upon the bottle, can be determined.

After the cap has been placed upon the bottle, it then becomes necessary to turn the lever down so as to securely lock the cap upon the bottle, and this operation must be accomplished while the bottle is still held under uniform compression in the cap, but in order to prevent any increase in the pressure during the locking operation, we pro-

pose to actuate the lever turning mechanism by means separate and distinct from the cap positioning means, and in the accomplishment of this we employ a lever turning finger S which is carried at the end ⁷⁰ of a rotary shaft S' , journaled to a suitable bearing carried at the forward end of a bracket S^2 , which is secured to the rear face of the pressure block as most clearly shown in Figs. 3 and 4. The shaft S' has a pinion ⁷⁵ S^3 connected thereto and which is engaged by a toothed sector S^4 pivotally mounted on a shaft S^5 fixed in a boss at the rear end of the bracket S^2 and this toothed sector has a downwardly extending radial arm S^6 to ⁸⁰ which one end of a spring T is connected, the opposite end of said spring being connected to the supporting frame.

The toothed sector is also provided with an upwardly projecting arm U , to which is attached a shackle U' and to which is connected a spring U^2 , the opposite end of said spring being connected to a similar shackle U^3 , which in turn is connected to the upper end of a lever V , said lever being ⁸⁵ pivoted adjacent to the side of the frame at V' adjacent the lower end of the lever and the extreme lower end of said lever is shaped and placed for engagement with a cam lever W rigidly mounted upon the treadle shaft and is positioned with reference to said cam as to engage the lower end of the lever after the cam has traveled the proper distance to elevate the bottle ⁹⁰ into engagement with the cap and maintain the same in such position, and when this has taken place, the cam lever W will engage the lower end of the lever V throwing the upper end rearwardly, actuating the toothed segment which in turn rotates the pinion attached to the shaft carrying the lever turning finger.

The cam lever W has a rearward extension W' to which a coil spring W^2 is attached in order to return the cam lever, treadles and cam to their proper positions after the capping operation has been accomplished and the treadles relieved of pressure.

By having the sector connected with springs upon opposite sides of its rotating center, the operation of the sector and the lever turning finger will be uniform, and in order to prevent too great a movement ¹¹⁵ during the turning operation we provide an adjustable stop X in the form of a headed screw which is inserted in a boss X' extending from the face of the frame so as to bring the stop screw X in the path of ¹²⁰ the sector arm U and by regulating this screw to the desired position, the movement of the sector can be arrested at the desired point.

In operation, a bottle is placed upon the ¹²⁵ table against the bottle gauge and a cap

is inserted in the chuck with its lever extending upwardly and against the end of plate N' and lip O'. The treadle is then pushed down and back with the result of elevating the bottle through the cam I and lever F and the mouth of bottle is forced into the cap, and maintained in this position, but there will be no excess pressure as the table is maintained steady after it has moved upwardly the amount permitted by the cam movement. The continued movement of the treadle causes the cam lever W to act upon the lever V and this in turn operates the toothed sector which drives the lever turning finger to complete the sealing operation by turning down the cap lever while the cap and bottle are held in fixed relation, and by having springs connected to both arms of the toothed sector, the movement thereof will be balanced and all danger of breakage due to too much force avoided. The stop X also limits the movement of the sealing mechanism.

Having thus described our invention, what we claim is:—

1. In a bottle capping machine, the combination with a movable bottle support and a chuck adapted to receive a cap having a lever, of a lever turning finger, a pivoted member adapted to actuate said lever turning finger and springs connected to the opposite ends of said pivoted member, one of said springs being connected to a fixed support and an actuating lever connected to the opposite end of the other spring.
2. In a bottle capping machine, the combination with a chuck and lever turning finger, of a bottle support, means including a cam for moving said bottle support a definite distance, a shaft upon which the cam is mounted, a member actuated from said shaft and a lever engaged by said member after the bottle support has reached the limit of its movement and means for actuating the lever turning finger connected to said lever.
3. In a bottle capping machine, the combination with a suitable supporting frame, of a chuck adapted to receive a cap, a lever turning finger operable in proximity to said chuck, a bottle support, a lifting lever for said support, a cam for actuating said lifting lever, a shaft on which said cam is mounted, a second cam mounted upon said shaft, a lever pivotally connected to the supporting frame, the second cam being adapted to engage the lower end of said lever, the upper end of said lever being connected with the finger turning means.
4. In a bottle capping machine, the combination with a chuck adapted to receive a cap having a lever, of a lever turning device carried by said chuck, a bottle support,

means including a cam for moving said bottle support to a predetermined point and then maintaining it stationary at said point, and means operated from the same source after the bottle support has reached its maximum movement, for operating the lever turning device.

5. In a bottle capping machine the combination with a frame, of a yieldable cap receiving chuck, a bottle support, a lever for lifting said support, a cam for operating said lever and maintaining the same in its raised position, a lever turning finger with pinion and segment for turning the same, a lever operatively connected with said segment, an arm upon the cam shaft adapted to actuate said lever, said arm engaging said lever while said cam is maintaining the bottle support in a definite raised position.

6. In a bottle capping machine, a chuck comprising a plate having a depending guide, a pair of oppositely disposed gripping fingers, said fingers being pivoted intermediate their ends to the sides of said plate, spring pressing means carried by said plate and actuating upon the rear ends of said fingers, the forward ends of said fingers being shaped to receive a cap.

7. In a bottle capping machine the combination with a chuck adapted to receive a cap, of a bracket rigidly connected to said chuck, a shaft journaled in said bracket and carrying a pinion and finger, a second shaft journaled in said bracket and carrying a toothed segment, said segment having arms projecting above and below its pivotal point, springs connected to said arms, one of said springs being connected to a fixed point, and a lever connected to the other of said springs for the purpose specified.

8. In a bottle capping machine the combination with a chuck adapted to receive a cap, of a bracket secured to said chuck, a lever turning finger carried by said bracket, an actuating segment also carried by said bracket, said bracket having oppositely extending arms, springs connected to said arms, one of said springs being connected to a fixed point, a lever connected to the other spring, a cam adapted to operate upon the opposite ends of said lever, and means for actuating said cam.

In testimony whereof, we hereunto affix our signatures in the presence of two witnesses.

EDMUND A. HEY.
JOHN G. LE PERE.
LYLE K. WEBBER.
